UNITED STATES PATENT OFFICE.

FRANK H. LINDNER, OF BAYONNE, NEW JERSEY.

STEAM-TURBINE.

No. 915,451.

Specification of Letters Patent. Patented March 16, 1909.

Application filed May 14, 1908. Serial No. 432,875.

To all whom it may concern:

Be it known that I, FRANK H. LINDNER, a citizen of the United States, and a resident of Bayonne, in the county of Hudson and State 5 of New Jersey, have invented certain new and useful Improvements in Steam-Turbines, of which the following is a specification.

My invention relates to elastic fluid turbines, and particularly to the buckets used in 10 connection therewith; and it has for its object the simple and ready construction of a bucket adapted to receive a stream of elastic fluid, deflect the same backwardly and divide and laterally discharge said stream.

15 In the accompanying drawings which illustrate my invention—Figure 1 is a side view of a series of buckets. Fig. 1^a is a section on the line 1^a—1^a, Fig. 1. Fig. 1^b is a partial sectional view illustrating the general arrangement of directing ports, buckets and exhaust chambers. Fig. 2 is a view of a portion of the turbine showing the exhaust chambers and the directing chambers. Fig. 2^a is a sectional view showing directing ports, 25 a modified form of bucket, exhaust ports, exhaust chambers and directing chamber. Fig. 3 is a partial side view showing a number of the modified buckets and a portion of the directing port. Figs. 4 and 5 are sectional views taken on the line 4—5, Fig. 3, looking in the direction of the right and left hand arrows respectively. Fig. 6 is a sectional view on the line 6—6, Fig. 3. Fig. 7 is a partial side view showing a modified form of the buckets 30 shown in Figs. 3 to 6. Figs. 8 and 9 are sectional views taken respectively on the line 8—8 and 9—9, looking in the direction of the arrows. Fig. 10 is a sectional view on the line 10—10, Fig. 7.

40 Similar characters of reference designate corresponding parts throughout the several views.

Referring to the drawings, 20 designates a rotating wheel disk suitably mounted and 45 crowned with a series of buckets 21. A casting 22 surrounds this wheel disk and terminates in an annular chamber 23 adapted to receive the buckets 21. An inlet 24, Fig. 2, is adapted to supply a suitable stream of 50 elastic fluid, such as steam to the buckets 21 through tangentially arranged directing ports 25, said fluid passing through and about said buckets in successive stages as set forth in my co-pending application Serial No. 55 370,763, filed April 29, 1907. As therein set

forth, the stream of fluid upon entering the buckets at the top is divided and backwardly deflected, being finally discharged through the sides of said buckets into exhaust chambers 26 at the sides of said buckets. These 60 chambers unite to form directing chambers 27 supplying the fluid to the buckets through succeeding directing ports 25, the exhaust chambers, directing chambers and directing ports increasing in volume proportionately 65 to suit the rate of expansion and the fluid being finally discharged into the atmosphere or into suitable condensing apparatus (not shown).

In the invention forming the subject of 70 the present application the buckets do not act in precisely the same manner as those of the aforesaid prior application, being of different construction. The general effect, however, is substantially the same in both 75 forms of turbines; but the division of the stream of fluid in the latter form is not simultaneous with the deflection of the same backwardly, but occurs thereafter.

As shown in Figs. 1, 1^a, 1^b, the buckets 80 consist essentially of blades 28 which are adapted to receive the stream of fluid and present a concave surface thereto so as to deflect the same backwardly. These blades terminate in walls 29 which separate successive buckets. Between these successive walls 29 is a central dividing wall 30 beginning at the bottom of the blades 28 and extending downwardly and outwardly with increasing cross-sectional area, the said walls 85 29 being conveniently secured thereto as shown in Figs. 1 and 1^a. This central dividing wall 30 with the walls 29 form the lateral outlet ports 31 of the buckets, which ports discharge the fluid laterally into the 90 exhaust chambers 26.

In Figs. 3 to 6 I have shown a modified form of bucket, the blades 28 presenting a uniformly concave surface to the said stream of fluid and their outer surface being convex 100 and intersecting the inner surface to form an upper and lower edge substantially perpendicular to the direction of the motion of the buckets. These blades are individually supported by a suitable central dividing stem or 105 wall 32, the stem of one bucket beginning as shown at or near the middle of the said convex surface and extending downwardly and outwardly with increasing cross-sectional area, and joins with the stem of the adjacent 110

bucket forming the lateral exhaust ports 31 adapted to discharge the stream of fluid laterally.

In Figs. 7 to 10 a modification in the manner of joining the stems of adjacent buckets is shown.

I claim:—

1. In a turbine: a wheel disk rotatably mounted; tangential directing ports to direct 10 a stream of elastic fluid; and a series of buckets upon the periphery of said wheel disk, said buckets being adapted to receive said stream, deflect the same backwardly, then divide the same and finally discharge said 15 divided stream laterally.
2. In a turbine: a wheel disk rotatably mounted; tangential directing ports adapted to direct a stream of elastic fluid; and a series of buckets upon the periphery of said 20 wheel disk adapted to receive said stream of fluid, said buckets consisting of blades presenting a concave surface toward said stream and of suitable supports for said blades, said supports forming a substantially continuous 25 ridge below the blades of the buckets, the said ridge being adapted to divide and then deflect laterally the stream of fluid, after it has left the blades of the buckets.
3. In a turbine: a wheel disk rotatably 30 mounted; tangential directing ports to direct a stream of elastic fluid; and a series of buckets upon the periphery of said wheel

disk, said buckets consisting of blades adapted to receive the said stream, presenting a concave surface thereto and deflecting the 35 said stream backwardly, and the said blades terminating in walls separating successive buckets; and a central dividing wall between successive walls, adapted to divide said backwardly directed stream and forming 40 with said separating walls lateral outlet ports to discharge said stream laterally.

4. In a turbine: a wheel disk rotatably mounted; tangential directing ports to direct a stream of elastic fluid; and a series of 45 buckets upon the periphery of said wheel disk, said buckets consisting of blades adapted to receive the said stream, presenting a concave surface thereto and deflecting the 50 said stream backwardly, and the said blades terminating in walls separating successive buckets; and a central dividing wall of increasing cross-sectional area downwardly 55 between successive walls adapted to divide said backwardly directed stream and forming with said separating walls lateral outlet ports to discharge said stream laterally.

Signed at New York in the county of New York and State of New York this 13th day of May A. D. 1908:

FRANK H. LINDNER.
